UNITED STATES PATENT OFFICE

SAMUEL BABITZKY, OF CHICAGO, ILLINOIS

DESIGN FOR A BASE FOR BIRD-CAGE STANDS OR SIMILAR ARTICLES

Application filed June 23, 1930. Serial No. 36,134. Term of patent 3½ years.

To all whom it may concern:

Be it known that I, SAMUEL BABITZKY, a citizen of the United States, residing at Chicago, in the county of Cook and State of Illinois, have invented a new, original, and ornamental Design for Bases for Bird-Cage Stands or Similar Articles, of which the following is a specification, reference being had to the accompanying drawing, forming a part thereof, in which—

I claim:

The ornamental design for a base for bird cage stands or similar articles, as shown.

In testimony whereof I affix my signature at 10 South La Salle Street, Chicago, Illinois.

SAMUEL BABITZKY.
